CLAIM

I claim the ornamental design for a compressor shroud, as shown and described.

DESCRIPTION

FIG. 1 is a perspective view of a compressor shroud embodying the ornamental design of my invention;

FIG. 2 is a side view of the compressor shroud of FIG. 1;
FIG. 3 is an opposite side view of the compressor shroud of FIG. 1;

FIG. 4 is a front view of the compressor shroud of FIG. 1;
FIG. 5 is a rear view of the compressor shroud of FIG. 1;
FIG. 6 is a top view of the compressor shroud of FIG. 1;
FIG. 7 is a bottom view of the compressor shroud of FIG. 1;
FIG. 8 is a perspective view of a compressor shroud comprising a second embodiment of the ornamental design of my invention;

FIG. 9 is a side view of the compressor shroud of FIG. 8;
FIG. 10 is an opposite side view of the compressor shroud of FIG. 8;

FIG. 11 is a front view of the compressor shroud of FIG. 8;
FIG. 12 is a rear view of the compressor shroud of FIG. 8;
FIG. 13 is a top view of the compressor shroud of FIG. 8;
and,

FIG. 14 is a bottom view of the compressor shroud of FIG. 8.

The broken line showings in FIGS. 1-14 are for illustrative purposes only and form no part of the claimed design.
